DIVERTING SWITCH

Felix W. Borse, Oak Park, and Henning S. Hermanson, Deerfield, Ill., assignors to Minneapolis-Honeywell Regulator Company, Minneapolis, Minn., a corporation of Delaware

Application May 6, 1944, Serial No. 534,506

20 Claims. (Cl. 251—101)

1

Our present invention relates to a diverting switch of the plug valve type which may be mounted on the back of a control panel and is operated by a knob in front of the panel.

One object of the invention is to provide a diverting switch of simple and inexpensive construction having a number of advantages that contribute to long life, fool-proof effortless operation, and to convenient servicing of the valve when necessary without removing the valve body from the panel or disconnecting any of the pipe connections with the valve body.

Another object is to provide a switch of this character particularly for switching compressed air from a supply main to various branches and bleeding other branches as desired through a rotatable plug valve structure provided with detent means for indicating various proper positions of port alignment.

Still another object is to provide a plug valve which may be lapped to secure a perfect seat of the plug within its bore and which has the ends of the bore and the ends of taper of the plug so related as to prevent the formation of ridges during the lapping operation, peripheral grooves in the valve body and in the valve plug likewise being related so as to prevent formation of ridges from lapping.

A further object is to provide a floating connection between a control shaft and the valve plug so that the plug cannot be accidentally loosened in its bore nor tightened by pushing or pulling of the control shaft and substantially constant seating pressure of the valve plug is maintained.

Still a further object is to provide a diverting switch which has a control shaft for the valve plug connected therewith by means of a detent head which is pinned to one end of the shaft and has a tongue and keyway connection with the plug, the other end of the shaft being journalled in the plug adjacent one end thereof and detent mechanism being provided for coaction with the detent head.

An additional object is to provide a detent cap removably positioned on the back of the valve body and having the detent head journalled therein for removal therewith, the control shaft being also removable from the valve plug with the detent head and the detent cap, thereby exposing the valve plug for removal and disassembly of all the parts for replacement of any of them without disturbing the piping to the valve body or removing the valve body from the panel on which it is mounted, and the in-

2

terior of the valve plug being threaded for coaction with a tool therewith for removal of the plug relative to the valve body.

With these and other objects in view, our invention consists in the construction, arrangement and combination of the various parts of our device whereby the objects contemplated are attained, as hereinafter more fully set forth, pointed out in our claims and illustrated in the accompanying drawings, wherein:

Fig. 1 is a front perspective view of a diverting switch embodying our invention.

Fig. 2 is a rear elevation thereof.

Fig. 3 is a sectional view on the line 3—3 of Fig. 2 with the portion 3a thereof taken on the line 3a—3a of Fig. 2.

Fig. 4 is an elevation of the valve plug per se.

Fig. 5 is a sectional view on the line 5—5 of Fig. 3 showing a detent mechanism of the diverting switch.

Fig. 6 is a sectional view on the line 6—6 of Fig. 3 showing a pinned connection between a control shaft and a detent head of the switch.

Fig. 7 is a sectional view on the line 7—7 of Fig. 3 showing a tongue and keyway connection between the detent head and the valve plug, and

Fig. 8 is a sectional view on the line 8—8 of Fig. 3 showing peripheral grooves on the valve body and the valve plug as well as a porting arrangement and a slot in the valve plug.

On the accompanying drawings, we have used the reference numeral 10 to indicate a panel or the like on which our diverting switch may be mounted. The diverting switch includes a valve body B and a valve plug P as its main elements and the body is adapted for mounting on the panel as by means of suitable bolts or screws through openings 12 of attaching feet 14 formed on the valve body.

The valve body B has a tapered bore indicated at 16, one end of which is designated 16a and the other end 16b. These ends are the small and large ends respectively of the bore. Between the ends 16a and 16b is a peripheral groove 18 in the bore and its sides are indicated at 18a and 18b.

The valve plug P has a tapered part 20 to fit the tapered bore 16 and the small and large ends of this tapered part are indicated as 20a and 20b. The plug and the valve body also have cylindrical portions 19 and 22 which are not tapered. The valve plug has a peripheral groove 24 opening into the groove 18 and the sides of the groove 24 are indicated at 24a and 24b. The groove 24 is offset relative to the groove 18 in the direction toward the small end 20a of the valve plug P and

this causes the groove side 24b to overhang with respect to the groove side 18b whereas the groove side 24a is past the groove side 18a and therefore within the bore 16.

Similarly the plug end 20a is in overhanging relation to the front end 16a of the bore 16 and the end 20b of the tapered portion of the plug is within the bore 16 or past the end 16b. This arrangement has a definite purpose in that it prevents the formation of ridges during the lapping of the valve where they will interfere with the proper air sealing of the plug in the valve body. Such ridges will be on the plug at the front face of the valve body and in the bore 16 at the line 20b so that wear during lapping and subsequent wear due to operation of the valve will not develop shoulders in the bore at the small end of the plug and on the plug at its large end.

Preferably the body and plug are made of dissimilar metals such as brass and cast iron and are hand-lapped to fit each other. After lapping with an abrasive, a finishing operation is preferably performed with hot oil and graphite in order to lubricate the valve between the lapped surfaces.

The off-set arrangement of the edges 16a and 20a, 16b and 20b, 18a and 24b prevent the formation of ridges at points where they would be formed during lapping if the overhanging relation of these edges were reversed. This contributes to the production of a perfectly lapped valve and one which does not leak after the lapping has been completed even though subject to many thousands of operations during its service life. Furthermore, any wearing of the plug within the body eliminates the harm from formation of ridges at undesirable locations as described in connection with the lapping operation and a valve is thereby had which lasts much longer than usual without leaks developing. Where it is desirable to have communication between a port such as an inlet port 26 and the entire periphery of the valve plug at all times, the grooves 18 and 24 may be provided and would ordinarily complicate the lapping operation but by the off-set arrangement of edges as we have described, a valve of this kind can be lapped into perfect fit as readily as a simple valve plug.

The port 26 of the valve body B may be connected with a main such as a copper tubing compressed air line and the valve body has a single or any desired number of outlet ports 28 which may be connected to various branches extending to pneumatic thermostats, damper motors or the like. On the drawings we have shown, merely by way of illustration, four of the outlet ports 28 and these are suitably threaded for the reception of copper tube fittings or small pipes. The valve plug itself has a plurality of return ports 30 (in the illustrated instance 3) and a slot 32. The slot 32 communicates with the groove 24 for the purpose of connecting this groove with any of the four branch ports 28 whereas the other three branch ports communicate through the ports 30 with the interior or bore of the valve plug indicated at 34. This bore communicates with atmosphere as will hereinafter be described.

For operating the valve plug P, we provide a control shaft 36 which is connected to the plug by a detent head 38. The means of connection includes a cross pin 40 and a tongue and keyway connection wherein the tongues are illustrated at 42 and are formed on the detent head while the grooves are indicated at 44 and are milled into the portion 22 of the plug P. The tongue and

keyway connection, it will be noted, is off-set relative to the center of the shaft 36 so as to prevent the possibility of reassembling the parts in the wrong position at 180° from its intended position.

Adjacent the end of the shaft 36 opposite the cross pin 40 the shaft is journalled in a bearing sleeve 46 of the plug P. This sleeve may extend through an opening 48 of the panel 10 which is enlarged so that it is impossible for the panel to bear sidewise against the plug and thus tend to destroy its proper seating in the bore 16. A control knob 50 is mounted on the shaft 36 preferably by a pair of set screws 52 at right angles to each other and engaging flat spots 54 on the control shaft. The knob therefore may be replaced in its proper position on the shaft after a disassembling operation.

A pointer 56 is associated with the knob 50 for indicatory coaction with indicia 58 on the panel 10. The indicator may be rotatable on a sleeve 60 of the control knob 50 and may be locked relative thereto by a lock nut 62 and a screw 64.

The detent head 38 has a sleeve portion 66 journalled in a bore 67 of a cap 68. This cap is removable with respect to the valve body B as by three screws 70. The detent head is limited in its axial movement relative thereto by a stop plug 72, the head of which serves as a stop when the detent head 38 is moved to the left in Fig. 3. The stop plug 72 is also a vent plug as it is provided with a vent opening 74 extending therethrough from the inner end to atmosphere at the outer end. The vent 74 communicates with the interior of the detent head 38 and with the bore 34 of the plug P to permit escape of compressed air from the bore to atmosphere.

A spring 76 is interposed between the detent head 38 and the valve plug P as illustrated in Fig. 3 to maintain a constant seating pressure on the valve plug. The cross pin 40 extends through both the shaft 36 and the detent head 38, being preferably a tight fit in the head and a relatively loose fit in the control shaft 36. The ends of the pin are peened as indicated at 41 to retain it in assembled position.

The detent head 38 has a plurality of detent notches 78 therein as shown in Figure 5 which are adapted to receive a detent in the form of a ball 80 slidably in a bore 82 of the detent cap 68. The bore is plugged at 84 and interposed between the plug and the ball is a spring 86 for urging the ball to engage in the detent notches 78.

Practical operation

In the operation of our diverting switch, the knob 50 may be manipulated for rotating the plug P either right hand or left hand as desired. Although the porting arrangement can be varied considerably from that disclosed, we will describe the operations which take place with the type of diverting switch that is illustrated on our patent drawings.

In the position shown in Fig. 3, the main port 26 is connected with the branch port 28 through the grooves 18 and 24 and the slot 32. The other three branch ports 28 are being bled through the three ports 30 to the bore 34 of the plug P and through the center of the detent head 38 to the vent 74. Obviously a quarter rotation of the plug will connect the next successive branch port 28 to the main 26 and bleed the remaining branches and so on. Instead of this arrangement, the ports 28 may be main ports and the port 26 a branch port so that the branch can be

fed from any one of three sources. Obviously more slots 32 and less ports 30 could be provided for other switching arrangements.

When the knob 50 is rotated to any one of its four positions where the ports are properly aligned, such fact will be indicated to the operator by the detent ball 80 snapping into one of the notches 78, and in so doing, effecting a final positioning of the valve plug in its "port aligned" position. The hole 36a in the shaft 36 for the pin 49 is slightly larger than the pin itself to permit such final positioning and to give an indication to the user of such fact. The snapping of the ball into the notch can be slightly felt when it occurs.

During operation of the diverting switch, a constant pressure of the plug P in its seat 16 is maintained by the spring 76. This pressure cannot be decreased by pushing on the shaft 36 as axial movement of the shaft in this direction is stopped by the detent head 38 engaging the cap 68, the cap, in turn, being fixed as it is connected to the valve body B and the valve body is supported on the panel 10 and the tongue and keyway connection permits of such movement without the plug moving with them. Likewise the seating pressure of the plug can be increased only by a slight amount due to increase in the pressure of the spring 76 when the knob is accidentally or intentionally pulled away from the panel. In that case the detent head 38 is moved with the shaft 36 but is soon stopped in its movement by the head of the stop plug 72 engaging the back face of the detent cap 68. This engagement occurs before the left hand end of the detent head 38 or its tongues 42 engage a socket bottom 39 of the valve plug or the bottoms of the keyways 44 respectively. Also by journaling the shaft 36 at one end in the bearing sleeve 46 of the plug P and having the other end journalled at 66-67 in the detent cap 68, the plug P cannot be unseated by sidewise or vertical pressure on the knob 50, thus contributing to a valve that operates leak-proof under all operating conditions.

In connection with the servicing of the diverting switch, the set screws 52 may be loosened and the screws 10 removed whereupon the shaft 36, detent head 38 and detent cap 68 may be removed for replacement of any of the parts thereof or the spring 76. If at that time it is desirable to remove the plug P for any purpose, a tool or bolt having a properly threaded end may be manipulated for engaging such end with threads 37 formed in the plug whereupon the plug may be withdrawn.

After repairs or replacements have been made, the parts may be reassembled in the reverse order and both the assembly and the disassembly operations do not in any way interfere with the piping to the ports 26 or 28 nor do they necessitate the removal of the valve body from its mounted position on the back of the panel 10. Servicing of the valve in a minimum of time is therefore facilitated by our design.

Some changes may be made in the construction and arrangement of the parts of our device without departing from the real spirit and purpose of our invention, and it is our intention to cover by our claims any modified forms of structure or use of mechanical equivalents which may be reasonably included within their scope without sacrificing any of the advantages thereof.

We claim as our invention:

1. In a diverting switch of the character dis-

closed, a valve body having a tapered bore, a tapered valve plug therein, a spring biasing said valve plug toward seated position in said bore, a control shaft for rotating said valve plug and extending into the small end thereof, said small end having a bearing for said control shaft, and means at the large end of said valve plug for loosely connecting the inner end of said control shaft therewith, said means comprising a head having an off-center tongue and keyway connection with said valve plug and a loose cross pin connection with said control shaft.

2. In a diverting switch, a valve body having a tapered bore, a tapered plug therein, a spring biasing said plug toward seated position in said bore, a control shaft for rotating said valve plug and extending into the small end thereof, said small end having a bearing for said control shaft, and means at the large end of said valve plug for loosely connecting the inner end of said control shaft therewith.

3. In a switch of the character disclosed, a valve body having a tapered bore, a tapered valve plug therein, means biasing said valve plug toward seated position in said bore, a control shaft for rotating said valve plug and extending into the small end thereof, said small end journaling the outer end of said control shaft, and means at the large end of said valve plug for loosely connecting the inner end of said control shaft therewith including a head having an off-centered tongue and keyway connection with said valve plug.

4. In a switch of the character disclosed, a valve body having a tapered bore, a tapered valve plug seated therein, a control shaft for rotating said valve plug and extending into the small end thereof, said small end having a bearing for said control shaft, and said control shaft having a loose connection with the large end of said valve plug, said connection being slidable and non-rotatable.

5. In a valve structure, a valve body having a tapered bore, a tapered valve plug therein, a control shaft through said valve plug for rotating it, said valve plug having a bearing for said control shaft and a slidable and non-rotatable connection with the shaft, said connection being limited in its movement in a direction axially of said control shaft whereby the shaft can neither push nor pull the valve plug, and a spring interposed between said connection and said plug.

6. A diverting switch comprising a valve body having a tapered bore, means for mounting said valve body on the back of a panel with said bore normal to the panel and entirely back of it, a detent cap removably secured to the rear end of said valve body, a tapered valve plug in said bore, a detent head journalled in said detent cap at the large end of said valve plug, a spring interposed between said detent head and said valve plug for tending to separate the two, said detent head having notches in its periphery, a detent carried by said detent cap for engaging with said notches to indicate when said valve plug is in port alignment position, a tongue and keyway connection between said valve plug and said detent head, a control shaft having a portion journalled in the small end of said valve plug and extending from the front of said panel through said valve plug and into said detent head, a cross pin connection between said detent head and the inner end of said control shaft, a vented stop plug for said detent head to prevent the head from being pulled by the control shaft into engagement with

the valve plug, and thus prevent its axial movement with said shaft, said detent head and said control shaft being removable with said detent cap, said valve body having a port arrangement including communication with the interior of the valve plug surrounding said control shaft, along said control shaft, through said detent head and through said stop plug vent to atmosphere.

7. A diverting switch comprising a valve body having a tapered bore, means for mounting said valve body on the back of a panel with said bore normal to the panel and entirely back of it, a detent cap removably secured to the rear end of said valve body, a tapered valve plug in said bore, a detent head connected with said valve plug for rotation therewith and journalled in said detent cap at the large end of said valve plug, a spring interposed between said detent head and said valve plug for tending to separate the two, said detent head having notches in its periphery, a detent carried by said detent cap for engaging with said notches to indicate when said valve plug is in port alignment positions, a control shaft having a portion journalled in said valve plug and extending from the front of said panel through said valve plug and into said detent head, a vented stop plug for said detent head to prevent the head from being pulled by the control shaft into engagement with the valve plug, said detent head and said control shaft being removable with said detent cap, said valve body having a port arrangement including communication with the interior of the valve plug surrounding said control shaft, along said control shaft, through said detent head and through said stop plug vent to atmosphere.

8. A diverting switch comprising a valve body having a tapered bore, a detent cap removably secured to the rear end of said valve body, a tapered valve plug in said bore, a detent head journalled in said detent cap at the large end of said valve plug and operatively connected with said valve plug for simultaneous rotation therewith, a spring interposed between said detent head and said valve plug for tending to separate the two, said detent head having notches in its periphery, a detent carried by said detent cap for engaging with said notches to indicate when said valve plug is in port alignment positions, a control shaft having a portion journalled in said valve plug and extending into said detent head, a vented stop plug for said detent head to prevent the head from being pulled by the control shaft into engagement with the valve plug, said valve body having a port arrangement including communication with the interior of the valve plug surrounding said control shaft, along said control shaft, through said detent head and through said stop plug vent to atmosphere.

9. A diverting switch comprising a valve body having a tapered bore, a detent cap removably secured to the rear end of said valve body, a tapered valve plug in said bore, a detent head journalled in said detent cap at the large end of said valve plug, a spring interposed between said detent head and said valve plug for tending to separate the two, said detent head having notches in its periphery, a detent carried by said detent cap for engaging with said notches to indicate when said valve plug is in port alignment positions, a tongue and keyway connection between said valve plug and said detent head, a control shaft having a portion journalled in the small end of said valve plug and extending into said detent head, a cross pin connection between

said detent head and the inner end of said control shaft, a vented stop plug for said detent head to prevent the head from being pulled by the control shaft into engagement with the valve plug, and thus prevent its axial movement with said shaft, said valve body having a port arrangement including communication with the interior of the valve plug surrounding said control shaft, along said control shaft, through said detent head and through said stop plug vent to atmosphere.

10. A valve structure comprising a body having a tapered bore, means for mounting said valve body on the back of a panel with said bore normal to the panel and entirely back of it, a detent cap removably secured to the rear end of said valve body, a tapered valve plug in said bore, a detent head in said detent cap at the large end of said valve plug, a spring interposed between said detent head and said valve plug for tending to separate the two and seat the plug, said detent head being journalled in said detent cap and having notches in its periphery, a detent carried by said detent cap for engaging with said notches to indicate and aid in the positioning of said valve plug, a tongue and keyway connection between said valve plug and said detent head, a control shaft having a portion journalled in the small end of said valve plug and extending from the front of said panel through said valve plug and into said detent head and connected therewith, and means to limit said control shaft against axial movement independent of said valve plug and thus prevent axial movement of the plug with the shaft.

11. A valve structure comprising a body, a detent cap removably secured to said valve body, said valve body having a tapered bore, a tapered valve plug therein, a detent head in said detent cap, a spring interposed between said detent head and said valve plug for tending to separate the two and seat the plug, said detent head being journalled in said detent cap and having notches in its periphery, a detent carried by said detent cap for engaging with said notches to indicate and aid in the positioning of said valve plug, a connection between said valve plug and said detent head, a control shaft having a portion loosely journalled in said valve plug for free movement relative thereto and extending into said detent head and connected therewith, and means to limit said control shaft against axial movement to the extent that all of such movement is independent of said valve plug to prevent axial movement of the plug with the shaft.

12. A diverting switch comprising a valve body having a tapered bore, means for mounting said valve body, a cap removably secured to said valve body, a tapered valve plug in said bore, a head in said cap at the large end of said valve plug, means interposed between said head and said valve plug for tending to separate the two and thereby seat the valve plug, said head being journalled in said cap, a slideable and non-rotatable connection between said valve plug and said head, a control shaft having a portion journalled in the small end of said valve plug and operatively connected with said head, stop means for said head in said cap to prevent the head from being pulled by the control shaft into engagement with the valve plug, said head and said control shaft being removable with said cap, said valve plug having a threaded portion for engagement of a tool therewith for removing the plug from the body.

13. A diverting switch comprising a valve body having a tapered bore, means for mounting said valve body, a cap removably secured to said valve body, a tapered valve plug in said bore, a head in said cap at the large end of said valve plug, means interposed between said head and said valve plug for tending to separate the two and thereby seat the valve plug, said head being journalled in said cap, a slidable and non-rotatable connection between said valve plug and said head, a control shaft having a portion journalled in the small end of said valve plug and operatively connected with said head, stop means for said head in said cap to prevent the head from being pulled by the control shaft into engagement with the valve plug, said head and said control shaft being removable with said cap.

14. In a diverting switch of the kind described, a valve body adapted for mounting on the back of a panel, said valve body having a tapered bore, a valve plug seated therein, a control shaft extending from the front of the panel through said valve plug and journalled in an end of the plug adjacent the panel, a cap on said valve body at the other end of the plug, a head therein journalled with relation to said cap and loosely connected with said shaft and said valve plug for turning the plug by rotating the shaft, a spring interposed between said plug and said head, means for limiting axial movement of said head toward said plug to prevent the head from imparting axial movement to the plug upon axial movement of said control shaft, said plug having its small end extended beyond the small end of said bore and its large end terminating within the bore, peripheral grooves in said plug and said body and registering with each other for the transfer of fluid pressure from one to the other, said grooves being offset with the edge of the plug groove toward the small end of the plug within said bore and the edge of the plug groove toward the large end of the plug extending beyond the corresponding edge of said body groove to prevent the formation of ridges at undesirable points during lapping and/or operation of the valve.

15. In a diverting switch of the kind described, a valve body having a tapered bore, a valve plug seated therein, a control shaft extending through said valve plug and journalled in one end of the plug, a cap on said valve body at the other end of the plug, a head therein journalled with relation to said cap and slidably and non-rotatably connected with said valve plug, said head being operatively connected with said shaft for turning the plug by rotating the shaft, a spring interposed between said plug and said head, said plug having its small end extended beyond the small end of said bore and its large end terminating within said bore to prevent the formation of harmful ridges.

16. In a diverting switch of the character disclosed, a valve body having a tapered bore, a tapered valve plug therein, means biasing said valve plug toward seated position in said bore, a control shaft for rotating said valve plug, said plug having at one end a bearing for said control shaft and means at the other end of said valve plug for loosely connecting said control shaft therewith, said means comprising a head having a tongue and keyway connection with said valve plug, and means for limiting axial movement of said shaft to an extent preventing such

axial movement from causing said head to move said valve plug axially.

17. A diverting switch comprising a valve body, means for mounting said valve body on the back of a panel with said bore normal to the panel, a detent cap removably secured on the rear end of said valve body, said valve body having a tapered bore, a tapered valve plug therein, a detent head journalled in said detent cap at the large end of said valve plug, a spring interposed between said detent head and said valve plug in said detent cap and having notches in its periphery, a detent carried by said detent cap for engaging with said notches to indicate port alignment position of said valve plug, a slidable and non-rotatable connection between said valve plug and said detent head, a control shaft having a portion journalled in said valve plug and extending from the front of said panel through said valve plug and into said detent head, and an operative connection between said detent head and said control shaft.

18. In a diverting switch, a valve body having a tapered bore, a tapered plug therein, a spring biasing said plug toward seated position in said bore, a control shaft for rotating said valve plug and extending into the small end thereof, said small end having a bearing for said control shaft, and means at the large end of said valve plug for loosely connecting the inner end of said control shaft therewith, said means being arranged to insure assembly of said control shaft in only one position of rotation relative to said valve plug.

19. In a diverting switch of the character disclosed, a valve body having a tapered bore, a tapered valve plug therein, a spring biasing said valve plug toward seated position in said bore, a control shaft for rotating said valve plug and extending into the small end thereof, said small end having a bearing for said control shaft, and means at the large end of said valve plug for loosely connecting the inner end of said control shaft therewith, said means comprising a head having an off-center tongue and keyway connection with said valve plug.

20. In a diverting switch of the character disclosed, a valve body having a tapered bore, a tapered valve plug therein, a spring biasing said valve plug toward seated position in said bore, a control shaft for rotating said valve plug and extending into the small end thereof, said small end having a bearing for said control shaft, and means at the large end of said valve plug for loosely connecting the inner end of said control shaft therewith, said means comprising a loose cross-pin connection with said control shaft.
